UNITED STATES PATENT OFFICE.

EDWARD A. WAGNER, OF FORT WAYNE, INDIANA, ASSIGNOR TO GENERAL ELECTRIC COMPANY, A CORPORATION OF NEW YORK.

CASING FOR ELECTRICAL APPARATUS.

Application filed November 11, 1920. Serial No. 423,468.

To all whom it may concern:

Be it known that I, EDWARD A. WAGNER, a citizen of the United States, residing at Fort Wayne, county of Allen, State of Indiana, have invented certain new and useful improvements in Casings for Electrical Apparatus, of which the following is a specification.

My invention relates to casings for electrical apparatus adapted to be submerged in oil, such as transformers and the like, and to its object an improved arrangement of parts which is light and economical to manufacture and at the same time possesses mechanical strength sufficient to support adequately the weight of the encased electrical apparatus.

It has been the practice generally to house transformers and the like designed for supply service in casings of cast metal, for instance cast iron. The use of cast metal casings for this type of electrical apparatus is not wholly satisfactory for a number of reasons: chief among which may be mentioned the difficulty in obtaining castings uniformly non-porous and oil-tight, the expense involved in maintaining a sufficient variety of patterns and molders' flasks to supply the desired variety of castings, and the disproportionately large dead weight of metal in the casings to that in the apparatus itself which it is necessary to support and transport where cast metal casings are used.

In the practice of my invention these objections are entirely obviated because I make use of sheet metal casings which are constructed mainly of parts welded together, light parts being largely employed because I support the whole weight of the encased apparatus from the sides, thus relieving the bottom from the shearing strains otherwise impressed by the weight of the encased apparatus.

For a more complete understanding of the nature and objects of my invention, reference should be had to the following detailed description taken in connection with the accompanying drawing in which:

Fig. 1 is a vertical section of a tank or casing for a supply transformer constructed in accordance with my invention; Fig. 2 is a top plan view of the tank shown in Fig. 1; Fig. 3 shows in perspective a detail in the transformer supporting means employed in

the tank shown in Figs. 1 and 2; Fig. 4 is a vertical section of a modified form of tank embodying my invention; and Fig. 5 shows a detail in the transformer supporting means employed in this modified form of tank.

Referring now to the drawing, 10 denotes the body portion of the tank or casing for a transformer 11, indicated by broken lines. The casing is shown without the usual cover, which is substantially square in shape in order to fit snugly on the top band 12 secured about the upper end of the tank.

The body portion of the tank does not follow the generally square outline of the top-band 12, but is bent along vertical lines so as to conform to the generally cruciform contour indicated in the plan in Fig. 2, thereby providing corner pockets 13, 14, 15 and 16 inside the top-band, the bottoms of which are closed by perforated inserted pieces, as indicated at 17 in Fig. 1. These inserted pieces are secured in place preferably by welding and are provided with one or more perforations of any suitable shape to receive and support the insulating bushings (not shown) through which the electrical conductors leading to the transformer 11 pass. In order that the conductors may readily pass from the transformer into the pockets 13, 14, 15 and 16, a suitable notch is cut in the top of the wall of the body portion 10, as indicated at 18 in Figs. 1 and 2.

The bottom portion 19 is preferably secured to the body portion by welding and need be thick enough merely to support the weight of oil or other cooling medium contained in the tank and in which the contained electrical apparatus is submerged.

The means for supporting the transformer 11 from the side walls of the tank, in the form of my invention shown in Figs. 1 and 2, comprise a pair of channel members 20, the bottom ends of which are closed by an inserted piece 21 which is clearly illustrated in Fig. 3. These channel members 20 are secured in any suitable manner (as by spot welding) to opposite sides of the tank and are adapted to engage with the outside legs of the core of the transformer 11. The transformer 11 is here indicated as of the distributed core type having four outer legs, two oppositely disposed ones being adapted to slide in the channel members 20 and rest upon the inserted pieces 21 in the ends. It

will of course be understood that where the transformer is of a different type the channel members 20 will have a correspondingly different disposition about the walls of the tank.

In order that the weight of the transformer may be borne as a pure shearing strain by the securing means without tensile strains tending to pull the members 20 away from the walls of the tank, the members 20 are extended and securely welded to the casing walls above the upper part of the transformer, increased strength being thus secured.

In the form of my invention shown in Fig. 4, the wall of the body portion 30 of the tank is made of corrugated sheet metal instead of plain metal in order that the walls may be stiff in both a lateral as well as in a transverse or vertical direction when bent to have the required configuration. The outline of the encased transformer is indicated by the broken line 31 in the tank, the latter having a top-band 32 which is offset from the contour of the body portion 30 to form the pockets as at 33 and 34. These pockets have perforated bottoms inserted as indicated at 37, the top of the wall of the tank being notched, as at 38, to provide easy passage of the conductors from the transformer at 31 into the pockets which contain bushings (not shown).

A pair of angle members 40, secured to the tank wall at opposite sides, here comprises the means for supporting the transformer 31. These angle members have in-

serted pieces 41 secured to their respective lower ends and are disposed with respect to each other on the wall of the tank so that they form what is in effect a pair of oppositely disposed channel members in which the outside legs of the core of the transformer 31 may slide and rest on the inserted pieces. Here again, these members 40 are extended and securely welded to the casing walls above the upper part of the transformer to secure increased strength.

Having now described an embodiment of my invention which is at present the best means known to me for carrying the same into effect, I would have it understood that this is merely illustrative and that I do not mean to be limited thereby to the precise details shown, nor restricted in the choice of recognized equivalents except as defined in my claim hereunto annexed.

What I claim as new and desire to secure by Letters Patent of the United States, is:

A casing for a transformer, said casing comprising sheet metal bottom and wall portions and being provided with vertically disposed channel members on the inner surfaces of its walls, said channel members being formed to engage the transformer and having their lower ends closed to provide supports therefor, the upper ends of the channel members being extended and welded to the casing walls above the upper part of said transformer.

In witness whereof, I have hereunto set my hand this 8th day of November, 1920.

EDWARD A. WAGNER.
